CLAIM

The ornamental design for a beverage bottle holding a crystal, substantially as shown and described.

DESCRIPTION

FIG. 1 is a front perspective view of a beverage bottle holding a crystal showing the new design;

FIG. 2 is a front elevational view of a beverage bottle holding a crystal showing the new design;

FIG. 3 is a rear elevational view of a beverage bottle holding a crystal showing the new design;

FIG. 4 is a side elevational view of a beverage bottle holding a crystal showing the new design;

FIG. 5 is an opposing side elevational view of a beverage bottle holding a crystal showing the new design;

FIG. 6 is a top plan view of a beverage bottle holding a crystal showing the new design; and,

FIG. 7 is a bottom plan view of a beverage bottle holding a crystal showing the new design.

The broken lines shown in the drawings depict portions of the beverage bottle that form no part of the claimed design.
